UNITED STATES PATENT OFFICE

138,148

DESIGN FOR AN OPTICAL FRAME

Robert Weber and Edward Salvage,
New York, N. Y.

Application July 21, 1943, Serial No. 110,728

Term of patent 7 years

(Cl. D57—1)

To all whom it may concern:

Be it known that we, Robert Weber and Edward Salvage, citizens of the United States and residents of the city of New York, in the county of New York and State of New York, have invented a new, original, and ornamental Design for an Optical Frame, of which the following is a specification, reference being had to the accompanying drawing forming a part thereof.

Fig. 1 is a front view of an optical frame showing our new design;

Fig. 2 is a top view thereof with the temple pieces broken away; and

Fig. 3 is a side elevation of the same.

Our design for an optical frame of the specific configuration as shown is characterized by the curved upper portion of the frame and the parts leading toward the temple pieces, the lens portions sloping upward toward the side temples as shown.

We claim:

The ornamental design for an optical frame, substantially as shown and described.

ROBERT WEBER.
EDWARD SALVAGE.
